Ralph W. Wilson,
Inventor,

By his Attorneys, Dodson & Roe.

UNITED STATES PATENT OFFICE.

RALPH WM. WILSON, OF NEW YORK, N. Y., ASSIGNOR TO THEODORE W. FOSTER & BRO. CO., OF PROVIDENCE, RHODE ISLAND, A CORPORATION OF MAINE.

CONTAINER.

Application filed September 22, 1922. Serial No. 589,856.

To all whom it may concern:

Be it known that I, RALPH W. WILSON, a citizen of the United States, residing at New York, in the county of New York and 5 State of New York, have invented a new and useful Improvement in Containers, of which the following is a specification.

My invention relates to that class of boxes or containers which are designed to hold 10 a powder compact and rouge together with a puff therefor, and has for its object to provide a convenient construction whereby a ready access may be had to either the powder or the rouge with perfect ease and 15 yet the two will be contained in the same case although in separate compartments.

My means of accomplishing the foregoing may be more readily understood by having reference to the accompanying drawings 20 in which—

Fig. 1 is a perspective view of my improved device showing both the powder and rouge compartment open.

Fig. 2 is a top or plan view showing the 25 rouge compartment partially open.

Fig. 3 is a top or plan view showing the rouge compartment closed.

Fig. 4 is a similar view showing the rouge compartment fully open.

Fig. 5 is a vertical sectional view through 30 the center of my improved vanity case.

As shown in the drawings, my box comprises a container 10, in which is located a powder compact 11. The container 10 is 35 closed by a lid 12 which is hinged thereto at 13. The lid 12 is hollow and has formed therein a circular depression 14 adjacent its periphery. This depression 14 may be formed by stamping the depression in the 40 top 15 of the cover 12 or the depression may be secured by brazing or soldering or in any suitable or desired manner.

Within this depression is mounted a rouge 45 compact 19. Normally the depression is covered by an outer cover 16 which is mounted upon the box cover 12, its periphery being turned over as at 17 to form means for holding the cover on the box cover but at the same time to permit of its rotation 50 thereon, its outer cover 16 is provided with

an aperture 18 which corresponds to the size of the depression 14. A vertical cylindrical wall of the box cover 12 is adapted to telescope the upper part of the container 10 and abuts against the shoulder 20 formed 55 thereon. A suitable powder puff 21 is mounted and rests upon the powder compact 11 being located between the top of the powder compact 11 and the mirror 22 forming the bottom of the box cover 12. 60 The rouge compact is preferably fastened in the depression 14, so that it will remain in position when the operator is making use of the mirror to apply the rouge.

It may be desirable in some instances to 65 change the location of the rouge container as well as to change the manner of closing it. I recognize that these changes may be made without departing from the scope of my invention and I do not desire to be 70 limited to the specific structure shown which merely illustrates a preferred embodiment of my invention.

Having described my invention what I 75 regard as new and desire to obtain by Letters Patent is:

1. The combination with a powder container, a cover hinged to said powder container, a rouge container of smaller size than the powder container mounted in said 80 cover, an outer cover for said container cover rotatably secured to said cover, there being an aperture therein corresponding to the size of the rouge container.

2. The combination with a powder container, a cover hinged to said powder container, a rouge container of smaller size than the powder container mounted in said cover, an outer cover for said container cover rotatably secured to said cover, there 85 being an aperture therein corresponding to the size of the rouge container, a mirror in said container cover, a powder puff, in said powder container intermediate the powder and the mirror, and a powder puff located in the rouge container.

In testimony whereof I have signed the foregoing specification.

RALPH WM. WILSON.
